(57) **CLAIM**

The ornamental design for a “removable cutting assembly for a printer”, as shown and described.

DESCRIPTION

FIG. 1 is a front and right side perspective view of a removable cutting assembly for a printer, showing my new design;

FIG. 2 is a back and right side perspective view thereof;

FIG. 3 is a front elevational view thereof;

FIG. 4 is a back elevational view thereof;

FIG. 5 is a right side elevational view thereof;

FIG. 6 is a left side elevational view thereof;

FIG. 7 is a top side plan view thereof; and,

FIG. 8 is a bottom side plan view thereof.

The dot-dash lines represent boundaries of the claimed design and themselves form no part of the claim. The dashed lines show portions of the removable cutting assembly for a printer which form no part of the claimed design.
